UNITED STATES PATENT OFFICE.

MORRIS SCHWARTZ, OF NEW YORK, N. Y.

COLLAR.

1,355,920.

Specification of Letters Patent. Patented Oct. 19, 1920.

Application filed June 14, 1918, Serial No. 239,951. Renewed September 4, 1920. Serial No. 408,310.

To all whom it may concern:

Be it known that I, MORRIS SCHWARTZ, a citizen of the United States, residing in the city of New York, county of Kings, and 5 State of New York, have invented a certain new and useful Improved Collar, of which the following is a specification.

This invention is an improved collar, and, speaking generally, embodies a collar structure which is convertible into either a soft 10 collar or a stiff collar.

With the foregoing in view, the salient feature of the invention consists in providing the ends of the fold over portion of the 15 collar with tabs adapted to extend over the top of the collar into lapping engagement with the inner face of the collar band, and, I also preferably provide a pocket in, or 20 associated with, the end of each neck band in which the said tabs may be positioned.

A further feature of the invention consists in associating a guide, for the neck-tie, with the rear portion of the band and above the back collar button hole, through which 25 the tie may be threaded and which precludes its engagement with the collar button.

Features of the invention, other than those adverted to, will appear from the hereinafter detailed description, taken in 30 conjunction with the accompanying drawing and appended claims.

In the accompanying drawing I have illustrated the preferred practical embodiment of the invention, though this specific 35 form is typical and not exclusive of the different forms in which the invention may be given expression.

Referring to the drawing, Figure 1 is an inside view of a collar embodying this invention, the collar being shown as laid out flat;

Fig. 1^a is a view of the same collar folded and with a neck tie associated therewith.

Fig. 2 is a perspective section taken on the 45 line 2—2 of Fig. 1^a; and,

Fig. 3 is a similar section taken on the line 3—3 of Fig. 1^a.

In the drawings numeral 1 indicates the collar in its entirety, having the turned over 50 portion 2 and the band 3. Each end of the collar is provided with a tab such as the tabs 4 and 5, and while these tabs may be of any desired shape they are here shown of rectangular configuration. Each tab is preferably an extension of the upper part of the 55 turned over portion, whereby seams are

eliminated at the juncture of the tabs and the turned over portion. On the inner face of each end of the band, corresponding in position and shape to its adjacent tab, is a pocket 6, into which the tab may extend and thus be securely held in place in lapping engagement with the band. The pockets 6 are preferably formed between the plies of the band, though, if desired, they may be formed from an additional piece of fabric sewed to the band. In Fig. 1 the collar is shown as laid out flat with the tabs free from engagement with the pockets, but in Figs. 1^a and 2 the tabs are shown as folded 60 into the pockets and the collar ready for use.

If the collar is to be worn as a soft collar, the tabs are the only parts starched, and, after the collar is laundered, said tabs are inserted in the pockets, and manifestly, 65 they serve as efficient stiffeners to preserve the proper shape of the collar. By incasing the tabs in the pockets, they are protected from perspiration, which would, naturally, detract from their stiffening function, and, 70 moreover, a smooth inner surface is presented to the neck of the wearer.

If the collar is to be worn as a stiff collar, the entire collar is starched, in which event, if desired, the pockets may be dispensed with. However, the tabs may be inserted 75 in the pockets and left unstarched, while the band and turned-over portion may be starched and laundered as usual.

Referring to Figs. 1, 1^a and 3, 7 indicates a guide for a necktie 7', said guide being formed on the outer face of the band, intermediate the juncture of the band and turned over portion and the back button hole of the collar 8. Said guide may be 80 formed by slitting the outer ply of the band, as shown in Fig. 1 and extending lines of stitching 9, from one slit to the other. This provides an efficient means for holding the back of the tie in proper position and prevents interference of the back collar button with the tie.

It will be understood that the improvements described may be applied to any conventional form of turn-over collar, and that the collar described may be modified in specific details without departing from the spirit or substance of applicant's invention, the scope of which is commensurate with the 85 annexed claims.

It will be observed that there is no seam at the juncture of the tabs and collar band,

and, as a result, the collar, when used as a stiff collar, possesses marked durability over ordinary stiff collars, since, in the latter, the seams at the locations mentioned, cause cracking in the laundrying of the collars, thereby seriously lessening the durability of the collars.

Having thus fully described the invention, what I claim as new, and desire to secure 10 by Letters Patent, is:

1. As a new article of manufacture, a turn over collar having a tab and a pocket at each

end and so arranged and disposed that the tab may be inserted in the pocket to stiffen the end of the collar.

2. As a new article of manufacture, a turn over collar having a tab at one end and a pocket adjacent to the tab so that the tab may be inserted in the pocket to stiffen the end of the collar.

15 20
In testimony whereof, I have signed my name to this specification.

MORRIS SCHWARTZ.
